CLAIM

The ornamental design for a set of eye shields, as shown and described.

DESCRIPTION

FIG. 1 is a front perspective view of a set of eye shields showing our new design shown optionally attached to an optical device and a helmet;

FIG. 2 is a front perspective view thereof with the helmet omitted;

FIG. 3 is a rear perspective view thereof;

FIG. 4 is a front perspective view thereof with the optical device omitted;

FIG. 5 is a rear perspective view thereof;

FIG. 6 is a front elevational view thereof;

FIG. 7 is a rear elevational view thereof;

FIG. 8 is a left-side elevational view thereof;

FIG. 9 is a right-side elevational view thereof;

FIG. 10 is a top plan view thereof; and,

FIG. 11 is a bottom plan view thereof.

The broken lines illustrate portions of the set of eye shields that form no part of the claimed design.
